(57) CLAIM

The ornamental design for syringe housing of a syringe injection safety device, as shown and described.

DESCRIPTION

FIG. 1 is a top and front perspective view of a syringe housing of a syringe injection safety device in accordance with a first embodiment;

FIG. 2 is a top and left side perspective view thereof;

FIG. 3 is a front elevational view thereof, with a rear elevational view being a mirror image;

FIG. 4 is a left side elevational view thereof, with a right side elevational view being a mirror image;

FIG. 5 is a top plan view thereof;

FIG. 6 is a bottom plan view thereof;

FIG. 7 is an enlarged fragmentary view of a portion of the syringe housing shown in FIG. 4; and

FIG. 8 is an enlarged front and left side perspective fragmentary view of a portion of the syringe housing shown in FIGS. 3; and

FIG. 9 is an enlarged rear and right side perspective fragmentary view of the portion of the syringe housing shown in FIG. 3.

FIG. 10 is a front elevational view of a syringe housing of a syringe injection safety device in accordance with a second embodiment;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is an enlarged fragmentary view of a portion of the syringe housing shown in FIG. 10;

FIG. 17 is an enlarged fragmentary view of a portion of the syringe housing shown in FIG. 12;

FIG. 18 is an enlarged front and right side perspective fragmentary view of the portion of the syringe housing shown in FIGS. 12; and,

FIG. 19 is an enlarged rear and right side perspective fragmentary view of the portion of the syringe housing shown in FIG. 12.

The broken lines in the drawings illustrate portions of the syringe housing of a syringe injection safety device and form no part of the claimed design.
